W. CLEVELAND.
FOUNTAIN PEN.

No. 10,469.

Patented Jan. 31, 1854.

UNITED STATES PATENT OFFICE.

WILLIAM CLEVELAND, OF ORANGE, NEW JERSEY.

IMPROVEMENT IN FOUNTAIN-PENS.

Specification forming part of Letters Patent No. 10,469, dated January 31, 1854.

To all whom it may concern:

Be it known that I, WILLIAM CLEVELAND, of Orange, county of Essex, and State of New Jersey, have invented a new and useful Improvement in Fountain-Pens, of which the following is a full, clear, and exact description, reference being had to the accompanying drawings, in which—

Figure 1 is a perspective view of the improvement. Figs. 2, 3, 4, 5, and 6 are different views of the pen, exhibiting the general construction.

In fountain-pens hitherto essayed there have been principally two difficulties—viz., a too rapid flow of ink or an insufficient supply to the pen—and in that class of pens where the flow is regulated by pressure or mechanical contrivance the inconvenience of adjustment has been a practical objection to the use of the pen. A fountain-pen to be successful must be self-feeding or automatic, and when the flow of ink is exactly in accordance with the necessity of the writer it becomes a very desirable instrument.

Fountain-pens have been made with small conduit-tubes to convey the ink to the pen; but the difficulty with them all is that the delivery-aperture being necessarily small the ink does not flow out freely, being retained by the capillary attraction of the little tube and the pressure of the atmosphere. If a small bubble of air could enter this little tube, then a corresponding portion of ink would flow out; but the capillary attraction of the parietes of the tube or orifice prevents the air from entering.

My improvement consists in counteracting the effect of this attraction by the introduction of a secondary capillary force in such manner as to break up the ring of liquid at the orifice of the tube and conduct the liquid out at one side of the orifice and allow the air to enter at the opposite side.

To effect this I introduce the leading-stem

a into the orifice and toward one side of the same, as shown in the drawings. It will be readily seen that the narrow space between this stem and the edge of the orifice, and between the stem and the shield of the pen below the orifice, forms a capillary space down which the ink will flow as fast as it is consumed by the use of the pen, while through the larger space opposite the air enters to preserve the equilibrium of pressure within and without the fountain. The leading-stem, which is a small shank of metal, is provided with a shoulder turned a little conical to answer the purpose of a stopper to close the orifice when the pen is not in use. The stem is continued down to the slit of the pen, and all the way the capillary action is kept up by the interstice between it and the shield of the pen. The stem is attached to a sliding arm *b*, which runs a short distance into the barrel of the pen and has at its upper extremity a little pin *d*, attached to it and working in a slot *e*, after the manner of sliding pens or pencils. The stopper may be pushed in and out by means of the stud *b'* or the pin *d*. With this pen in every case of variation of either stem or orifice the relation of the capillary forces must be such that they will be greater on the delivery side than on the side where the air enters.

I do not claim the employment of capillary action to supply the ink to the pen, except when used under an arrangement and combination like that herein set forth, said arrangement and combination consisting in the employment of the leading-stem so fixed in the delivery-aperture that it shall lead the ink down on one side of the aperture and allow the air to enter the other, in the manner and upon the principles herein set forth.

WM. CLEVELAND.
